UNITED STATES PATENT OFFICE

2,596,304

INDEXING GRINDING FIXTURE

Roy Stegall, Chicago, Ill.

Application September 16, 1949, Serial No. 116,154

2 Claims. (Cl. 51—216)

1

This invention relates to work-holding fixtures, and more particularly to a fixture to be used with a grinding machine to index and grind a work piece to polygonal shape with its faces parallel to a predetermined axis.

It is among the objects of the invention to provide an improved work-holding fixture in which a work piece can be exactly centered and which can be mounted on a grinding machine and operated to present work piece faces in predetermined angular relationship to each other to the grinding wheel of the machine and maintain such faces exactly parallel to the axis on which the work piece is centered, which is operative to position the work piece for grinding one or more pair of mutually parallel faces thereon, so that work pieces of different shapes can be produced including work pieces of square or rectangular, hexagonal, octagonal and other polygonal cross-sectional shapes, and which is simple in construction, is adjustable to receive work pieces of different sizes, is easy to mount on a conventional grinding machine, and is economical to manufacture.

Other objects and advantages will become apparent from a consideration of the following description and the appended claims in conjunction with the accompanying drawings, wherein:

Figure 1 is a top plan view of a fixture illustrating of the invention;

Figure 2 is a front end elevation of the fixture;

Figure 3 is a rear end elevation of the fixture;

Figure 4 is a longitudinal cross-section on an enlarged scale on the line 4—4 of Figure 1;

Figure 5 is a side elevation on an enlarged scale of a fragmentary front portion of the fixture;

Figure 6 is a cross-section of a fragmentary portion of the fixture taken on the line 6—5 of Figure 4; and

Figure 7 is an elevational view substantially on the plane of the line 7—7 of Figure 4.

With continued reference to the drawings, the work-holding fixture comprises, in general, a base 10 of generally U-shaped formation having a pair of spaced-apart, apertured lugs or legs, a tail stock socket 11 mounted in one of the legs and projecting outwardly therefrom, a tail stock 12 adjustably threaded into the socket 11, a head plate 13 rotatably mounted in the other lug or leg of the frame, a head stock 14 mounted in the head plate 13, a handle 15 secured to the head plate and positioned at the outer side of the frame leg in which the head plate is journaled, a locking pin 16 slidably mounted in a bore in the handle 15 and selectively engageable in a series

2

of apertures provided in the head-plate-carrying leg of the frame and arranged at substantially equal angular intervals in a circle centered on the axis of rotation of the head plate, and a work-piece-engaging dog 17 engageable with a work piece centered between the tail stock 12 and the head stock 14 and connected to the head plate 13 for rotating the work piece with the head plate.

The base 10 has a rectangular bight 18 formed of suitable material, preferably of a magnetic character, and of sufficient weight and thickness so that the base can be held on a magnetic grinding machine table. An upstanding leg or lug 19 is provided at one end of the bight 18 and is of rectangular shape with an extension 20 at the mid-length location of its upper edge in which extension an aperture 21 is provided to receive the tail stock socket 11.

The tail stock socket 11 has a reduced cylindrical portion 22 secured in the aperture 21 and terminating in an angular shoulder which bears against the outer face of the extension 20 surrounding the aperture 21 to positively locate the socket relative to the frame leg 19. The socket 11 is an elongated, tubular body having a bore therethrough and a screw-threaded counterbore opening to the end of the socket opposite the end secured in the frame leg 19.

The tail stock 12 is an elongated pin having a conically-pointed inner end 23 engageable with the work piece 24 and having on its opposite end a knurled head 25. Adjacent the head 25 the tail stock is provided with external screw threads threadable into the screw-threaded counterbore of the socket 11, so that the tail stock is adjustable longitudinally of the socket upon rotation of the tail stock by the knurled head 25. A knurled lock nut 26 is threaded onto the tail stock at the outer end of the socket for locking the tail stock in adjusted position relative to the socket.

At its end opposite the lug 19, the frame bight 18 is provided with an upstanding leg or lug 27 of elongated, rectangular shape which extends from the bight 18 a distance greater than the leg 19. This leg 27 is provided with an aperture 28 which has a common center line with the aperture 21, but is larger than the aperture 21. The leg 27 is also provided with a plurality of apertures 29 arranged at substantially equal angular intervals around a circle centered on the center line or axis of the aperture 28. The apertures 29 are preferably so spaced that two of them are centered on a line perpendicular to the frame bight 18 and extending through the center line of the aperture 28, and two others, disposed at respectively-op-

posite sides of the aperture 28, are centered on a line perpendicular to the first-mentioned line and also passing through the center line of the aperture 28 with the remaining apertures arranged in pairs respectively disposed at opposite sides of the aperture 28 and centered on lines passing through the center line of this aperture.

The head plate 13 comprises a flat disc 30 having an elongated notch 31 opening to the periphery thereof and having on one side a concentric, cylindrical boss or hub 32 journaled in the aperture 28 and provided with a concentric aperture or bore 33.

The handle 15 comprises a crank having a circular end portion 34 of substantially the same diameter as the diameter of the hub 32 of the head plate, a short shaft 35 projecting radially from one side of the portion 34 and a cylindrical handle 36 projecting perpendicularly from the shaft 35 at the end of the shaft opposite the portion 34. The handle 36 is provided with a bore 37 which slidably receives the locking pin 16. This locking pin comprises an elongated, cylindrical shank 38, and a knurled head 39 secured on this shank at the outer end of the handle 36. This locking pin is selectively engageable in the apertures 29 by sliding it inwardly and outwardly of the handle 36.

The crank 15 is secured to the hub of the head plate by suitable means, such as the two cap screws 39, particularly illustrated in Figure 6, extending through registering apertures in the circular portion of the crank and into screw-threaded wells or bores in the hub 32, and two dowel pins 40, particularly illustrated in Figure 4, which are centered on a line substantially perpendicular to a line extending through the centers of the screws 39 and which also extend through apertures in the circular portion of the crank and into wells or recesses provided in the hub 32.

The circular portion of the crank is provided with an aperture of the same size as the aperture in the hub of the head plate and registering with the hub aperture, and the tail stock 14 comprises a cylindrical shank 41 received in and closely fitting the bore in the head plate hub 32 and the aperture in the crank 15 and having at one end an annular bead or flange 42 partly received in a counterbore in the head plate at the end of the bore 33 opposite the crank 15. Beyond the shoulder or flange 42 the head stock is reduced in size and provided with a conically-pointed end 43 for engagement with the work piece 24.

The work-engaging dog 17 comprises a metal ring of square or rectangular cross-sectional shape, having two diametrically-opposed, screw-threaded bores 44 and 45 extending radially therethrough, and a well or recess 46 opening to one side of the ring and disposed at substantially 90 degrees from the bores 44 and 45. A pin 47 is secured at one end in the recess 46 and projects perpendicularly from the ring for engagement in the notch 31 of the head plate, and set screws 48 and 49 are threaded into the bores 44 and 45, respectively.

In the use of the fixture, a work piece 24 is centered in the fixture by adjustably moving the tail stock 12 and engaging the work piece at the opposite ends of a predetermined axis between the tail stock 12 and the head stock 14. The tail stock is then locked by the lock nut 26 to hold the work piece centered in the fixture and, with the pin 38 engaged in the uppermost aper-

ture 29 and the dog 17 surrounding the work piece with its pin 47 engaged in the notch 31 of the head plate, the work piece is rotated to a position such that one of the faces thereon to be ground flat is disposed directly below the grinding wheel 50 of the grinding machine, the frame of the fixture being secured on the machine table. The machine table is then moved to pass the work piece beneath the grinding wheel and returned to its original position, whereupon the locking pin 16 is released and the crank 15 rotated through 180 degrees, the pin re-engaged in the corresponding aperture 29, and the table again operated to pass the work piece beneath the grinding wheel. After the fixture and work piece have been returned to their original position, the crank 15 is returned to its original position and another cut made on the first face of the work piece. This process may be continued, gradually lowering the grinding wheel toward the center of the work piece until the two faces are properly ground, as determined by checking the faces with a micrometer caliper. If other flat faces are desired on the work piece, the locking pin is engaged in another selected one of the apertures 29 for the first pass or cut, and is then moved to the aperture disposed 180 degrees from the last selected aperture, and a pass or cut made, and this process is also repeated until the two additional faces have been brought to the proper positions, as indicated by a micrometer caliper. By continuing this process, as many faces can be ground onto the work piece as there are apertures 29 in the leg 21 of the frame, and these faces will all be centered on the rotational axis of the work piece and substantially parallel thereto. However, all of the faces will not necessarily be the same distance from the rotational axis of the work piece.

If it is desired to grind the faces parallel to a bore or hole provided through the work piece, the pointed ends of the head and tail stocks of the fixture are inserted into respectively-opposite ends of such a hole or bore and the ground faces will then be exactly parallel to such hole or bore in the work piece.

By means of the fixture, the work piece is properly and positively centered and can be quickly moved to different angular positions to provide the desired ground faces thereon.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A work-holding fixture for a grinding machine comprising a base having longitudinally spaced and aligned vertical legs, a tail stock horizontally mounted through one of the legs and longitudinally adjustable relative to the opposing leg, a head plate rotatably journaled to the inner face of the opposing leg, a head stock disposed through said head plate and longitudinally aligned with the tail stock, said head plate being rotatable on the head stock, a crank fixed to the journaled portion of the head plate to rotate the plate, a pin slidably mounted transversely in the crank, said leg being formed with a plurality of

transverse apertures concentrically arranged around the head stock and selectively longitudinally alignable with the pin, and a workpiece engaging dog spaced from and engaged with the head plate to rotate therewith.

2. A workpiece holding fixture for a grinding machine comprising a base, a pair of longitudinally spaced and aligned vertical first and second posts on said base, a horizontally disposed longitudinally adjustable tail stock mounted in the first post, a head stock mounted in the second post and longitudinally aligned with the tail stock, a head plate rotatably disposed on the inner face of the second post and having a hub portion rotatable on the head stock and extending through the second post, a crank secured to the hub at the outer face of the second post for rotating said head plate, said second post having a plurality of transverse openings formed therein and concentrically arranged around the head stock, a pin slidably mounted transversely in the

crank and selectively engageable in the apertures to latch the head plate against rotation, a work engaging dog adapted to be vertically interposed between the head and tail stocks for engaging a work piece centered between the stocks and means on said dog detachably engaging a means on the head plate for rotation therewith.
